UNITED STATES PATENT OFFICE.

DAVID GILES, OF NASHVILLE, TENNESSEE, ASSIGNOR TO HIMSELF AND
CALEB B. ISBESTER, OF SAME PLACE.

IMPROVEMENT IN APPARATUS FOR BLACKWASHING MOLDS.

Specification forming part of Letters Patent No. 154,754, dated September 8, 1874; application filed
June 10, 1874.

To all whom it may concern:

Be it known that I, DAVID GILES, of Nashville, in the county of Davidson and State of Tennessee, have invented certain new and useful Improvements in a Process of Blackwashing Pipe-Molds; and I do hereby declare the following to be a full, clear, and exact description of the invention, such as will enable others skilled in the art to which it pertains to make and use it, reference being had to the accompanying drawings, which form part of this specification.

My invention relates to an improvement in an apparatus for and process of blackwashing pipe-molds; and consists of an elevated tank, rubber-hose pipe, double funnel-shaped nozzle, pipe, stop-cock, and the process of applying the wash.

Figure 1 is the entire apparatus as it appears when in use. Fig. 2 is a vertical section of the hose-pipe, nozzle, stop-cock, and top of pipe-mold.

A is an elevated water-tight tank, of any required dimensions, from the bottom of which is an escape or outlet pipe, a. B is an ordinary rubber hose, of any length and dimensions required. This hose is attached by one end to outlet-pipe a, and to the other end is attached the flaring-nozzle pipe D. D is a flaring-nozzle pipe, consisting of a pipe with a stop-cock and a flaring nose. In the mouth of this funnel-shaped nose is a concaved stop or distributer, b, that does not fill up the entire interior circumference of the nozzle-pipe, leaving room between the periphery of the stop b and the interior of the pipe D for a fluid to pass. C is an ordinary stop-cock. E shows one end of a pipe-mold or flask in position to receive the blackwash.

The pipe-mold or flask is prepared in the usual way, and is placed perpendicular in position to be reached by tube B. The double-flaring-nozzle pipe is placed over the end of the flask, as shown in Fig. 1, the stop-cock turned to permit the fluid blackwash to flow into the flaring nozzle, where it is met by the convex face of the distributer b, and passes in a flood over the inner surface of the flask or pipe-mold, coating the entire interior uniformly with the wash.

The advantages of my invention are, first, no hard substance that could mar or derange the sand is permitted to pass into or through the molds; second, by admitting and distributing the wash from one end of the tube the mold is more evenly coated.

Having now fully described my invention and the mode of using it, so that those skilled in the art may be able to fully understand and use it, what I esteem as my invention and desire to protect by Letters Patent, is—

1. The flaring-nozzle pipe D, having concaved bottom b, perforated stays, and continuous discharge-opening, as described and set forth.

2. The process of blackwashing pipe-molds by introducing and distributing the wash at the upper end by means of a circular slotted nozzle, and allowing it to gravitate to the bottom, substantially as described, and in the manner set forth.

In testimony that I claim the foregoing I have hereunto set my hand this 25th day of May, 1874.

DAVID GILES.
